UNITED STATES PATENT OFFICE.

LOUIS SCHLESINGER AND HERMAN E. HEINE, OF MILWAUKEE, WISCONSIN, ASSIGNEES TO BRADLEY WASHFOUNTAIN COMPANY, OF MILWAUKEE, WISCONSIN, A CORPORATION OF WISCONSIN.

OVERHEAD-SUPPLY WASHFOUNTAIN.

Application filed June 17, 1925. Serial No. 37,782.

To all whom it may concern:

Be it known that we, LOUIS SCHLESINGER and HERMAN E. HEINE, citizens of the United States, and residents of Milwaukee, in the county of Milwaukee and State of Wisconsin, have invented new and useful Improvements in Overhead-Supply Washfountains, of which the following is a description, reference being had to the accompanying drawings, which are a part of this specification.

This invention relates to overhead supply washfountains.

Sanitary washfountains now in general use permit a number of persons to wash at the same time, and to accomplish this, a circular basin or receptacle of comparatively large diameter, is provided with a circular fountain which discharges a circular spray of water into the receptacle. In fountains of this type the vent and the water supply pipes usually extend downwardly through the floor, the vent pipe extending to the outside atmosphere and the water pipes to a source of supply. In many buildings the washfountains are placed in the basement, or on a cement floor, and it is impractical to extend the pipes downwardly without tearing up the floor. In some places it is possible to lay the vent in the floor or ground, and in cases of this kind it is desirable to take the water supply from above.

It is one of the objects of the present invention to overcome the before mentioned objectionable features and provide a washfountain in which the water supply pipes extend upwardly to a source of supply and the flow be directed in a manner to prevent splashing when discharged from the fountain for use.

A further object of the invention is to provide a washfountain construction in which the spraying portion thereof is supported by means independent of the vent pipes and the water supply pipes.

A further object of the invention is to provide a washfountain having means above the spray fountain for mixing hot and cold water so that the desired temperature may be obtained at the fountain.

A further object of the invention is to provide an overhead supply washfountain which is of simple construction, is strong

and durable and is well adapted for the purpose described.

With the above and other objects in view the invention consists of the improved overhead supply washfountain and its parts and combinations as set forth in the claims, and all equivalents thereof.

In the accompanying drawing in which the same reference characters indicate the same parts in all of the views:

Fig. 1 is a vertical sectional view of a washfountain provided with the improved overhead water supply; and

Fig. 2 is a transverse sectional detail view taken on line 2—2 of Fig. 1.

Referring to the drawing the numeral 5 indicates a basin or receptacle preferably of annular form, which is supported upon a standard 6. The basin may be of any shape or formed of any suitable material desired. The basin is formed with a strainer and outlet opening 7, and is connected to a discharge coupling 8 mounted centrally beneath the basin which is adapted to have a vent pipe and trap (not shown) connected thereto. The strainer and outlet openings 7 are formed in a flanged coupling member 9 to which an upstanding supporting tube 10 is connected. A fountain 11 is mounted on the upper end portion of the supporting tube 13 and if desired a tube 12 (indicated by dotted lines) may be connected to the coupling member 8 and the fountain 11 to firmly hold the parts together. The fountain is of circular form and is provided with a circular line of downwardly inclined orifices 12' through which the water is sprayed for use. The lower side of the fountain is formed with a groove 11' into which the tube 10 extends to center the fountain on the tube and to form a more secure connection therewith. An inner tube 13 is connected to the lower inner portion of the fountain while an outer tube 14 is connected to the upper portion of the fountain and the space 15 between these two tubes forms the water supply duct or pipe for the fountain. The upper end portions of these pipes 13 and 14 are connected, respectively, to upper and the lower walls of a supplemental annular mixing and coupling member 16 and form a water-tight connection therewith. Water supply pipes 17 and 18 having controlling valves 19 and 20 are con-

100
105

nected to the opposite sides of the mixing member to supply tempered water to the fountain. The upper portions of these pipes 17 and 18 extend inwardly at right angles 5 and are connected to a mixing chamber 20' which is mounted on the upper end portion of the inner tube 13 but closed therefrom. This mixing chamber is of annular form and is provided with an upper central opening 21 for receiving the lower end portion of a mixing valve 22. Upwardly extending pipes 23 and 24 supply hot and cold water to the valve 22 and said valve is formed with a tubular valve member 24 10 having ports 25 and 26 provided in the opposite sides thereof. Said valve member may be turned by the handle 27 to register its ports 25 and 26 with the openings to which the upwardly extending pipes 23 and 24 are connected to regulate the relative amount of water flowing from the pipes 23 and 24 into the mixing chamber. The valves 15 19 and 20 permit turning on the tempered water from either side of the washfountain. 20 A soap dish and receptacle 25 may also be mounted on the outer pipe 14 if desired.

From the foregoing description it will be seen that the improved overhead supply washfountain is of very simple construction 25 and is well adapted for the purpose described.

What is claimed as our invention is:

1. An overhead supply washfountain, 30 comprising a standard having a basin thereon, a tubular member extending upwardly from the basin, a fountain mounted on the tubular member and having a line of spray openings, another tubular member connected to the fountain and surrounding the first 35 mentioned tubular member and extending upwardly from said fountain to form a water conduit between the two tubes, a mixing chamber above the tubular member, and valved controlled means for supplying water to the mixing chamber.

2. An overhead supply washfountain, 40 comprising a standard having a basin thereon, a supporting member extending upwardly from the basin, a fountain mounted on the supporting member and having a circular line of spray openings, an inner tube connected to the fountain and extending upwardly therefrom, an outer tube connected to the fountain and extending upwardly therefrom, the space between said tubes forming a water conduit to the fountain, a supplemental mixing chamber connected to the tubes, a mixing chamber positioned above the supplemental mixing chamber, a conduit means between the two chambers, valve means controlling the flow through said conduit, overhead hot and cold water supply pipes connected to the mixing chamber, and valve means controlling the flow of hot and cold water to the mixing chamber.

3. An overhead supply washfountain, 45 comprising a standard having a basin thereon provided with a discharge opening, a supporting tube extending upwardly from the basin, a fountain mounted on the supporting tube and having a circular line of spray openings, an inner tube connected to the fountain and extending upwardly therefrom, an outer tube connected to the fountain and extending upwardly therefrom, the space between said tubes forming a water conduit to the fountain, a supplemental mixing chamber connected to the tubes, tubes connected to the supplemental chamber and extending upwardly therefrom, a mixing chamber connected to the upper end portions of said last mentioned tubes, valves for said tubes for controlling the flow of tempered water to the fountain, overhead hot and cold water supply pipes connected to the mixing chamber, and valve means controlling the flow of hot and cold water to the mixing chamber.

4. An overhead supply washfountain, 50 comprising a standard having a basin thereon provided with a central discharge opening, a supporting tube extending upwardly from the discharge opening, a fountain mounted on the supporting tube and having a circular line of spray openings, an inner tube connected to the fountain and extending upwardly therefrom, an outer tube surrounding the inner tube in spaced relation and connected to the fountain and extending upwardly therefrom, a supplemental mixing chamber connected to the upper end portions of the spaced tubes, the space between said tubes forming a water conduit to the fountain, other tubes connected to the supplemental mixing chamber and extending upwardly therefrom, valves controlling the flow through said last mentioned tubes, a mixing chamber connected to the upper end portions of said last mentioned tubes, overhead pipes connected to the mixing 55 chamber, and a valve connected to the mixing chamber for controlling the relative flow of water from the overhead pipes.

5. An overhead supply washfountain, 60 comprising a standard having a basin thereon provided with a central discharge opening, a supporting tube extending upwardly from the discharge opening, an annular fountain mounted on the supporting tube and having a circular line of spray openings for directing streams of water outwardly and downwardly, an inner tube connected to the fountain and extending upwardly therefrom, an outer tube surrounding the inner tube in spaced relation and connected to the fountain and extending upwardly therefrom, a supplemental mixing chamber connected to the upper end portions of the spaced tubes, the space between 65 said tubes forming a water conduit to the

fountain, other tubes connected to the opposite sides of the supplemental mixing chamber and extending upwardly therefrom, valves for said pipes for controlling the flow of water from either side of the fountain, a mixing chamber interposed between and connected to the upper end portions of the last mentioned tubes, a valve connected to the

mixing chamber, and overhead hot and cold water supply pipes connected to said last 10 mentioned pipes.

In testimony whereof, we affix our signatures.

LOUIS SCHLESINGER.
HERMAN E. HEINE.
